CONTROL KNOB FOR AN ELECTRICAL SWITCH

David E. Scott, Royal Oak, Mich., assignor to Square D Company, Park Ridge, Ill., a corporation of Michigan

Filed July 6, 1965, Ser. No. 86,025

Term of patent 14 years

(Cl. D26—13)

Fig. 1.

Fig. 2.

Fig. 3

Fig. 4.

Fig. 5.

Fig. 6.

FIGURE 1 is a perspective view of a control knob for an electrical switch showing my new design;

FIGURE 2 is a top plan view of the control knob of FIGURE 1;

FIGURE 3 is an elevational view taken generally from the front of FIGURE 1;

FIGURE 4 is an elevational view taken generally from the front of FIGURE 1, with portions in diametrical section;

FIGURE 5 is a perspective view of the control knob shown in FIGURE 1, but showing a modified embodiment thereof wherein portions of the upper surfaces are smooth rather than ribbed; and

FIGURE 6 is a top plan view of the embodiment of FIGURE 5.

I claim:

The ornamental design for a control knob for an electrical switch, substantially as shown and described.
